GILPIN MOORE, OF MOLINE, ILLINOIS, ASSIGNOR TO DEERE & COMPANY,
OF SAME PLACE.

Letters Patent No. 67,131, dated July 23, 1867.

IMPROVEMENT IN DIES FOR MAKING PLOUGH-BRACES.

The Schedule referred to in these Letters Patent and making part of the same.

TO ALL WHOM IT MAY CONCERN:

Be it known that I, GILPIN MOORE, of Moline, in the county of Rock Island, and State of Illinois, have invented certain new and useful Improvements in Dies for Making Plough-Braces; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use said invention, I will proceed to describe it.

My invention consists in the construction of a set of dies for the manufacture of braces for ploughs, as hereinafter described.

Figure 1 is a face view of the upper die.

Figure 2 is a similar view of the lower die.

Figure 3 is a perspective view of the dies united.

Figure 4 is a side view of the dies, representing the positions of the blank during the process of being operated upon.

Figure 5 is an edge or end view of the lower die, with the upper die represented in place in red lines.

In the manufacture of ploughs of wrought iron and steel, such as are used in the prairie soils of the West and South, it is necessary to use a brace between the rear portions of the land-side and the mould-board; and this brace has to be made of a special form, adapted to the size and style of plough. Heretofore it has been customary to forge these braces by hand, which is a slow and expensive process. Besides, when thus made, it is almost impossible to make them perfectly uniform, thereby rendering the plough, when completed, more or less imperfect, and consuming much time in the fitting of the brace and the other parts. To obviate these difficulties, I propose to form these braces by means of dies, which I have constructed for that purpose.

I construct my dies of two blocks of metal, as represented by A and B, the former representing the upper and the latter the lower die. In the face of the block B, I cut a recess, a , of a size corresponding to the blank of which the brace is to be formed, these blanks being first cut in proper lengths from a bar of iron or steel of suitable width and thickness. This recess a is straight on the horizontal face of the block, the latter being bevelled at the line e near one edge, and the recess a being continued of the same width and depth along the face of the bevelled portion also, as shown in fig. 1. The upper block A is constructed with a smooth face, to fit on the face of B, and has a projecting lip, C, corresponding with the bevelled edge of block B, as shown in fig. 3. The blank being placed in the recess a , and the dies forced together, the end of the blank, where it projects over the inclined or bevelled face, is bent to correspond, and, when taken out, has the form represented by a' , the bent portion being indicated by o . Another recess, b , is also formed in the block B, as shown in fig. 1, of proper size to receive the piece a' edgewise, the bottom of said recess being formed on a curve, as represented by the red lines in fig. 4, and a recess, b' , being formed in the upper block A, as represented in fig. 2, this latter recess being made convex on its surface, and running out to the surface at the line e , where the projecting lip C begins, the rear end of said recess being deep enough to permit the end of the blank to rise up therein, as it is bent into the form represented by b' , when the dies are again brought together. A portion of the face of the block B is made lower than the rest, as represented by D of fig. 1, the block A having a corresponding projection, D'. The rear portion of the face of block B is then bevelled off along the line u , at an angle of about forty-five degrees, more or less, forming a depression, as shown at P of fig. 1, the block A having a corresponding projection, P', as represented in fig. 2. A horizontal lip, r, projects from the side of the plane part of the face of B, as shown in figs. 1 and 5, to hold the brace b' in position while being finished. After it has been bent into the form represented by b' it is placed on block B in the position represented by c of fig. 1, when, by pressing the dies together, the end is bent down over the inclined surface, along the line u , which completes the brace, and giving to it the form represented by c' in perspective, the end o being thus bent and made to stand at just the angle required to fit against the land-side, and the end n being bent at the proper angle to fit the mould-board, while the body between these parts is curved or bent edgewise sufficiently

to bring the outer faces of the parts *n* and *o* at the required inclination in the horizontal plane, to adjust them to the corresponding surfaces of the land-side and mould-board.

By these means I am enabled to form the braces with great rapidity and perfect uniformity, and thus to make a better and cheaper plough.

Having thus described my invention, what I claim, is—

The dies A and B, constructed substantially as shown and described, for making plough-braces, as set forth.

GILPIN MOORE.
